(57) **CLAIM**

The ornamental design of a replacement cassette tape for
tape transfer device, as shown and described.

DESCRIPTION

FIG. 1 is a Front View of our replacement cassette tape for
tape transfer device;

FIG. 2 is a Rear View thereof;

FIG. 3 is a Left Side View thereof;

FIG. 4 is a Right Side View thereof;

FIG. 5 is a Top Plan View thereof;

FIG. 6 is a Bottom View thereof;

FIG. 7 is a section taken in the direction of arrows 7—7 in
FIG. 5;

FIG. 8 is a section taken in the direction of arrows 8—8 in
FIG. 1;

FIG. 9 is a section taken in the direction of arrows 9—9 in
FIG. 1; and,

FIG. 10 is a front elevation view showing the claimed design
in place within a holder, which has been depicted by means
of broken lines for illustrative purposes only and forms no
part of the claimed design.
